J. A. CALDWELL AND C. S. BUGBEE, OF SPRINGFIELD, MASSACHUSETTS.

Letters Patent No. 89,465, dated April 27, 1869.

IMPROVEMENT IN WHIP-SOCKETS.

The Schedule referred to in these Letters Patent and making part of the same.

To all whom it may concern:

Be it known that we, J. A. CALDWELL and C. S. BUGBEE, both of Springfield, Hampden county, Commonwealth of Massachusetts, have invented a new and useful Improved Whip-Socket; and we do hereby declare that the following is a full and clear description thereof, reference being had to the accompanying drawings, and to the letters of reference marked thereon.

In the drawings—

Figure 1 is a sectional view,
Figure 2, a plan view, and
Figure 3, a side view of our invention.

This invention consists of a new and improved socket for whips, which is easily and cheaply manufactured, and yet more durable and perfect in its operation than those now in use.

It consists in construction of a socket, A, turned up from a solid piece of wood, the grain of the same ordinarily running lengthwise.

The method of attaching this socket A to the carriage may be varied to suit circumstances, but the way we prefer to accomplish this is by the use of the two straps, B and B, which are connected in a peculiar

manner, as shown in fig. 2 more particularly, where it is seen that a continuous strap is passed around the socket A and through the dash-board, or other supporting portion of the vehicle, both ends being fastened together, and between the socket A and the support, by means of a screw-rivet, H, and nut, I.

By this means we obtain an excellent socket, manufactured at a very slight cost, and easily attached by means of the bands already described.

Now, having described our invention,
What we claim as new, and desire to secure by Letters Patent, is—

1. As a new article of manufacture, a whip-socket, turned up of wood, substantially in the manner shown.
2. The method of fastening the same, consisting of the two straps, B and B, passed around and fastened together, between the socket and support, by the rivet, substantially as shown.

J. A. CALDWELL.
C. S. BUGBEE.
